UNITED STATES PATENT OFFICE.

NATHAN D. WHITE, OF AKRON, OHIO, ASSIGNOR TO TAPLIN, RICE & CO.,
OF SAME PLACE.

RECEPTACLE FOR POT-HOLE LIDS.

SPECIFICATION forming part of Letters Patent No. 223,422, dated January 6, 1880.

Application filed October 23, 1879.

To all whom it may concern:

Be it known that I, NATHAN D. WHITE, of Akron, in the county of Summit and State of Ohio, have invented certain new and useful 5 Improvements in Receptacles for Pot-Hole Lids; and I do hereby declare the following to be a full, clear, and exact description of the invention, such as will enable others skilled in the art to which it pertains to make and 10 use it, reference being had to the accompanying drawings, which form part of this specification.

My invention relates to stoves; and it consists in the combination of parts hereinafter 15 described and claimed.

In the drawings, Figure 1 represents a stove provided with my device. Fig. 2 is a plan view of the same, the dotted lines indicating the operation of my attachment.

20 A is the body of a cooking-stove. B B are the pot-hole lids or covers. C is a receptacle for containing the lids or covers B that may not be in use, and D is a swinging arm, to which is secured the receptacle C. As the 25 lids B are removed they are to be placed in the receptacle C, and moved out of sight and out of the way by swinging the arm D be-

near the hearth. This arm D is secured to a pivotal rod, E, whose upper extremity is fitted in a hole, a, in the hearth, and whose lower 30 extremity is seated in a hole, b, formed in the lower flange, c, of a stove, and in line with hole a.

What I claim is—

1. The combination, with a stove, of a swinging arm provided with a cover-receptacle, said arm being pivotally connected both to the hearth and to the lower flange of the stove, substantially as set forth. 35

2. The combination, with a stove having its 40 hearth and its lower flange, respectively, provided with holes in line with each other, of a swinging arm carrying a cover-receptacle, and a rod connected thereto, whose upper and lower extremities work as pivots in said hearth 45 and flange-holes, substantially as set forth.

In testimony whereof I have signed my name to this specification in the presence of two subscribing witnesses.

NATHAN D. WHITE.
